UNITED STATES PATENT OFFICE.

RALPH H. TUCKER, OF LOS ANGELES, CALIFORNIA.

AIR-LIFT PUMP.

Application filed June 9, 1924. Serial No. 718,794.

This invention consists of the novel features herein shown, described and claimed.

The leading object is to make an air pump for deep wells having the largest practical piston area in proportion to the size of the oil tubing string.

Another object is to make an improved air driven pump piston and cylinder mechanism for that type of deep well pumps in which the oil tubing string is provided with a seat for the pump mechanism and the pump mechanism is connected to the air pipe and lowered into the tubing and has a shoulder to rest upon the seat so that the entire pump mechanism may be inserted or removed by operating the air pipe.

Other objects and advantages will appear from the drawings and specification.

The drawings illustrate an air pump for deep wells embodying the principles of my present invention.

Figure 1 is a vertical diametrical section of a well, a well casing and the air driven pump.

Fig. 2 is a cross section on the line 2—2 of Fig. 1.

Fig. 3 is an enlarged sectional detail on the line 3—3 of Fig. 2.

The details of construction and operation shown in the drawings are as follows:

The well hole 1 and the well casing 2 may be any of the usual constructions and conditions.

The oil tubing string 3 may be of any desired size that will pass freely into the well casing 2. A reducer coupling 4 is placed upon the lower end of the oil well string 3 and has a beveled internal seat 5 within the vertical plane of the chamber 6 in the oil well string. A pump cylinder housing 7 is screwed upwardly into the reducer coupling 4 and has a perforated cap 8 upon its lower end. The air pipe 9 is a string of practically the same length as the oil tubing string 3 and may be of any desired size that will pass freely into the oil tubing string 3. A spring seat 10 fits against the lower end of the air pipe 9. An expansive coil spring 11 fits upwardly against the spring seat 10. A hollow plunger buffer 12 fits against the spring 11 and has radial slots 13 formed from its lower end and producing teeth 14. A nipple 15 is screwed upon the lower end of the air pipe 9 and has a shoulder 16 engaging the spring seat 10. A spring housing 17 extends down-

wardly from the nipple 15 and has a shoulder 18 against which the flange 19 of the plunger 12 engages so as to support the plunger and spring.

A cylinder 20 extends downwardly from the housing 17 and has a spider 21 with a beveled finished outer face fitting upon the seat 5 to support the pump mechanism and the air pipe 9. A piston cylinder supporting member 22 is screwed upon the spider 21, there being ports 23 leading through the spider from the cylinder chamber 24. A piston cylinder head 25 is screwed into the lower end of the supporting member 22 and a piston cylinder 26 is screwed upon the head 25 against the member 22. A plug 27 is screwed into the lower end of the cylinder 26. A chamber 28 is formed from the upper face of the plug 27. An expansive spring 29 is mounted in the chamber. A buffer 30 is mounted upon the spring 29 and has a flange 31 extending from its lower part. A ring 32 is screwed into the top of the chamber 28 to engage the flange 31 and limit the upward movement of the buffer under the tension of the spring 29. Teeth 33 extend upwardly from the buffer 30, the upper ends of the teeth being all on a level.

A piston 34 is slidably mounted in the cylinder 26 and has a hollow stem 35 extending upwardly slidably through the cylinder head 25 and slidably into the cylinder 20. A valve 36 fits slidably in the hollow of the stem 35 and has a head 37 with a flat lower face adapted to fit upon the upper ends of the teeth 33. The head 37 has a beveled upper outer face 38 to fit a beveled valve seat 39 formed in the lower end of the hollow stem 35, so that when the piston 34 is down with the head 37 upon the teeth 33, the head 37 is in engagement with the seat 39 to close the passage around the valve 36 in the stem 35. Ports 40 are formed through the stem 35 above the cylinder head 25. Grooves 41 are formed longitudinally in the periphery of the valve 36 from the head 37 upwardly to points above the ports 40.

In forming the grooves 41, webs 42 are inserted across the upper ends of the grooves with the grooves extending inside of the webs to ports 43 above the webs. The webs 42 form port closures and cover the ports 40 when the air pressure is on to raise the piston 34, and uncover the ports 40 after the

- piston 34 has been raised and should go down. At this time the grooves 41 and the ports 40 serve as exhaust means to let the air out below the piston 34.
- 5 The valve 36 is tubular and when the head 37 is seated, the valve 36 extends above the stem 35 and has a head 44 closing the upper end of a chamber 45 of the valve, and the head has a flange 46 to engage the upper end 10 of the stem 35 and ports 47 below the flange, so that when the piston 34 is down, the head 44 is raised and the air pressure coming down the pipe 9 will pass through the ports 47, through the chamber 45, through the 15 teeth 33 to an expansion chamber 48 between the plug 27 and the piston 34, and the air pressure will raise the piston 34 to drive the oil out of the chamber 49 between the piston 34 and the cylinder head 25.
- 20 An annular plate 50 fits upon the head 25 and covers outlet ports 51 and 52 formed through the cylinder head 25.

Bolts 53 have heads 54. Expansion coil springs 55 are mounted upon the bolts 25 against the heads 54. Bores 56 are formed from the upper face of the head 25 and the bolts and springs are inserted into the bores. Spring seats 57 are screwed into the bores against the springs 55. The plate 50 is 30 placed in position with the bolts 53 extending through the plate and nuts 58 are screwed down upon the bolts against the plate.

The tensions of the springs 55 are exerted 35 to hold the plate 50 down to close the outlet ports 51 and 52 and support the load of oil in the oil tubing string 3 and chamber 24 and form outlet check valves so that when the piston 34 moves up, the oil in the chamber 49 will pass through the ports 51 and 52 and upwardly.

A plate 59 fits against the lower face of the head 25 and covers elbow-shaped inlet ports 60 and 61 leading from an inlet oil 45 chamber 62 to the chamber 49. Bolts and springs 63 and 64 hold the plate 59 yielding- 50 ly in position so as to form inlet check valves to hold the pressure in the chamber 49 when the piston 34 is going up, and to let the oil 55 into the chamber 49 when the piston 34 is going down. The oil chamber 62 communi- 60 cates with the oil in the well casing 2 through the perforated cap 8 so that as fast as the oil is pumped from the chamber 62, more oil 65 will flow upwardly through the cap 8.

When the piston 34 goes upwardly, the head 44 will strike the buffer 12 and the valve 36 will be moved downwardly in the stem 35, thereby closing the ports 47 and moving the 70 port closures 42 to open the ports 40 and moving the head 37 away from the seat 39, thereby allowing the air in the chamber 48 to pass upwardly through the grooves 41 and through the ports 43 and 40 into the oil in the chamber 24 and the air will pass up-

wardly through the oil in the tubing string 3 to the point of discharge, and this passage of air upwardly through the oil materially lightens the oil and stimulates the flow or reduces the load upon the piston 34 and 70 upon the head 25.

As soon as the air pressure has been sufficiently exhausted from the chamber 48, the air pressure upon the head 44 will move the stem 35 and the valve 36 downwardly until the head 37 strikes the buffer teeth 33 and continued downward movement of the stem 35 will bring the head 37 into the seat 39, then close the ports 40 and open the ports 47 so that the air pressure will pass downwardly to the chamber 48 and again raise the piston 34. There will be sufficient friction between the stem 35 and the valve 36 to carry the valve with the stem until the valve strikes either the buffer 12 or the 80 buffer 30.

Various changes may be made without departing from the spirit of my invention as claimed.

I claim:

1. In an air pump, the combination with 90 an oil tubing string and an air pipe string, of a reducer secured to the lower end of the oil tubing, an internal seat in the reducer, a housing extending downwardly from the reducer, a spider secured to the lower end of the air pipe and engaging the seat, a tubular cylinder extending from the air pipe through the spider, a cylinder supporting member extending from the spider downwardly, a cylinder head at the lower end of the supporting member and having inlet and outlet check valves, a piston cylinder extending downwardly from the cylinder, means forming a head in the lower end of the cylinder, a spring buffer in the head, a piston in the piston cylinder, a hollow stem extending upwardly from the piston slidingly through the first cylinder head and slidingly into the air pipe cylinder, there being air outlet ports through the hollow stem above the first cylinder head, and a hollow valve closed at its upper end and extending slidingly through the hollow stem and adapted to be reciprocated in the 100 stem by engagement with the buffers as the piston goes up and down, there being ports and port closing means operated by the reciprocation of the valve so as to let the air from the air pipe raise the piston and so 105 as to exhaust the air to lower the piston.

2. In an air pump having an air pipe inside 110 of an oil tubing, an air cylinder extending downwardly from the air pipe, a piston cylinder connected to the oil tubing and having 115 an upper cylinder head and a lower cylinder head, a piston in the piston cylinder between the heads, a hollow stem extending from the piston slidingly through the upper head and slidingly into the air cylinder,

- der, a valve slidably mounted through the hollow stem, intake and outlet check valves in the upper head, spring buffers for reciprocating the valve in the stem, there being ports and port closing means operated by the reciprocation of the valve for admitting air from the air pipe to the expansion chamber below the piston to raise the piston and for shutting off the air pipe pressure and exhausting the pressure from the expansion chamber to lower the piston. 70
3. In an air pump, a piston cylinder having an imperforate lower head and an upper head provided with intake and outlet check valves, a piston in the piston cylinder, an air pipe, and means for leading the air from the air pipe to the expansion chamber below the piston and for admitting the air pressure to, and exhausting the air pressure from, the expansion chamber below the piston. 75
4. An air lift pump comprising a barrel, an air pipe communicating with said barrel and providing an air cylinder, a piston reciprocable in said barrel and having a hollow stem reciprocable in said air cylinder, a valve closure adapted to open and close said hollow stem whereby air may be admitted to said barrel below said piston to lift the piston, or may be caused to move said piston, stem and valve closure downwardly by exerting pressure upon said stem and valve closure within said air cylinder, means including check valves for admitting fluid to said barrel above said piston and discharging it therefrom, and means for discharging the air from said barrel which is below said piston. 80
5. An air lift pump comprising a barrel and an air cylinder, a piston reciprocable in said barrel having a hollow stem reciprocable in said air cylinder, valve means cooperating with said stem for forming a piston in said cylinder or permitting air to pass through said stem into said barrel below said piston, means for actuating said valve means, means including check valves for admitting fluid to said barrel above said piston and discharging it therefrom, and means for releasing the air in the barrel which is below said piston. 85
6. An air lift pump comprising a barrel having its lower end closed, a head within said barrel, inlet and outlet check valves mounted upon said head, an air cylinder, means for supplying air to said air cylinder, a piston reciprocable in said barrel below said head and having a hollow stem reciprocable in said air cylinder, means adapted to open and close said stem whereby said stem and piston may be forced downwardly by the air in said air cylinder or air may be admitted to said barrel below said piston, and means for discharging the air in said barrel which is below said piston. 90
7. An air lift pump comprising a barrel having its lower end closed, a head within said barrel, inlet and outlet check valves mounted upon said head, an air cylinder, means for supplying air to said air cylinder, a piston reciprocable in said barrel below said head and having a hollow stem reciprocable in said air cylinder, means adapted to open and close said stem whereby said stem and piston may be forced downwardly by the air in said air cylinder or air may be admitted to said barrel below said piston, and means for discharging the air in said barrel which is below said piston into said barrel above said head. 95
8. An air lift pump comprising a barrel having its bottom closed, a piston reciprocable in said barrel, supply means for supplying fluid pressure to the barrel, valve means actuated upon movement of the piston for causing the fluid pressure to alternately move the piston upwardly and then downwardly, and means including check valves for admitting fluid to said barrel and discharging it therefrom. 100
9. An air lift pump comprising a barrel having a closed bottom, an air cylinder, a piston reciprocable in said barrel and having a hollow stem reciprocable in said air cylinder, means for alternately opening and closing said hollow stem, whereby air may force said stem and piston downwardly when said stem is closed and air may be admitted to said barrel below said piston for forcing said stem and piston upwardly when said stem is open, means for admitting a fluid to said barrel above said piston upon the downward movement of said piston, means for causing the fluid to be discharged upwardly upon the upward movement of the piston, and means for releasing the air in the barrel below the piston. 105
10. An air lift pump comprising a barrel having a closed bottom, an air cylinder, a piston reciprocable in said barrel and having a hollow stem reciprocable in said air cylinder, means for alternately opening and closing said hollow stem, whereby air may force said stem and piston downwardly when said stem is closed and air may be admitted to said barrel below said piston for forcing said stem and piston upwardly when said stem is open, means for admitting a fluid to said barrel above said piston upon the downward movement of said piston, means for causing the fluid to be discharged upwardly upon the upward movement of the piston, and means for releasing the air in the barrel below the piston into the lifted fluid. 110
11. An air lift pump comprising a barrel having a closed bottom, supply means for supplying fluid pressure to the barrel, conducting means for conducting the fluid pressure through the piston to the barrel below 115
- 120
- 125
- 130

the piston, means carried by the piston for alternately opening and closing said conducting means so that the fluid pressure may force the piston downwardly and then upwardly, means including check valves for admitting fluid to said barrel above said piston and discharging it therefrom, and means for releasing the fluid pressure from said barrel below said piston.

10 12. An air pump comprising a barrel having a closed lower end, a piston recipro-

cable in said barrel, means closing the upper end of the barrel provided with outlet and inlet check valves for admitting fluid to the barrel above the piston and discharging it therefrom, and means for alternately supplying and releasing pressure to the barrel below the piston to produce its reciprocation.

In testimony whereof I have signed my name to this specification.

RALPH H. TUCKER.
